ALVA A. FRYER, OF HAGERSTOWN, MARYLAND.

SAND-FEEDING DEVICE.

1,264,383.

Specification of Letters Patent. Patented Apr. 30, 1918.

Application filed December 23, 1915. Serial No. 68,428.

To all whom it may concern:

Be it known that I, ALVA A. FRYER, a citizen of the United States, residing at Hagerstown, in the county of Washington 5 and State of Maryland, have invented certain new and useful Improvements in Sand-Feeding Devices, of which the following is a specification.

My present invention relates to sand feeding mechanism that is especially designed for use in connection with conventional types of locomotives and like structures, for properly instigating the flow of sand from the sand dome to the desired points on the 10 track; and which has, for its general object, the provision of a novel device of this nature, that affords facilities whereby the hopper structure may be expeditiously attached or detached to or from the dome and 15 the force feed medium introduced thereto at a point exteriorly with respect to the dome.

Another object of my invention is to provide an improved sand feeding device such as pointed out above, which includes a hopper structure to be arranged in the dome so as to receive the sand by gravitational feed, the hopper being so constructed whereby it may be cast in a single piece and provision made for the introduction of the force feed 20 medium thereinto from a point exteriorly of the dome.

A further object of my invention is to provide an improved hopper construction that, as before stated, may be cast in a single piece 35 and cored out at suitable points to form a passage way and an adjacent nozzle member through which the force feed medium may be passed to move the sand from the hopper and thence to the respective feeding pipe.

Still another object of my invention is to provide an improved hopper structure as set forth above, that is insertible into the dome from a point exteriorly thereof without necessitating the removal of any of the sand 40 or in any way necessitating the going into the interior thereof, and which, when in place, is readily accessible to, from a point exteriorly of the dome so that the nozzle member may be cleaned and kept in such 50 condition with ease.

A yet further object of my invention is to provide an improved joint member that may be associated with the hopper structure exteriorly of the dome, that is designed to 55 properly conduct the sand to the respective feeding pipes and to eliminate backing up

or the rebounding of the sand, which, as a general rule, occurs in the conventional form of devices of this nature.

A still further object of my invention is 60 to provide a device of the type in question that is extremely simple in construction, strong and durable, and highly practical from both the standpoint of the manufacturer and the standpoint of the user; and 65 which, it is believed, may be manufactured at a comparatively low cost.

Various other objects and advantages will 70 become apparent during the continuance of the following description.

These objects are accomplished by such means as are shown in their preferred form in the accompanying drawings, described in the following specification and then more specifically pointed out in the appended 75 claims.

In the accompanying drawings wherein like characters designate like parts throughout the several views:—

Figure 1 is a view in horizontal section 80 showing the sand dome broken away and part of the joint construction in elevation;

Fig. 2 is a view in vertical section taken through the device as it appears in Fig. 1;

Fig. 3 is a view in detail of a member that 85 may be associated with the device for purpose of facilitating the cleaning of the nozzle member from a point exteriorly of the dome;

Fig. 4 is a view in horizontal section showing a slightly modified form of means for conducting the force feed medium;

Fig. 5 is a view in vertical section showing another modified form of introducing the force feed medium into the joint member 95 in a plane corresponding with the plane of the general extent of the respective feed pipes;

Fig. 6 is a view in top plan showing the device as it appears in Fig. 5;

Fig. 7 is a fragmentary view showing a slightly modified form of connection between the hopper structure and the sand dome.

In reducing my invention to practice, I 105 provide a tubular base 10, screw threaded as at 11 about a certain portion of its periphery for insertion through an opening 12 of the dome 13. The base 10 is further provided with an annular flange such as shown at 14, 110 in Fig. 1 which may be drawn tightly against the inner face of the side wall of the

dome when the device is positioned in place, whereby a secure connection may be attained.

A hopper structure 15 is preferably cast 5 with the base 10, such as shown in Fig. 1 and preferably arranged in the dome so as to receive the sand by gravitational feed. This hopper is in turn cored out longitudinally as at 16 to form a suitable passage way 10 for conducting the force feed medium, while it is further cored out transversely as at 17 to communicate with the interior bore 18 of a nozzle member 19. The nozzle member 19 is in turn provided with a longitudinally extending outlet bore 20 and a counter bore 21, the former serving to increase the velocity of 15 the force feed medium, while the latter serves a purpose that will subsequently appear. Although I do not wish to limit myself in any way to means for connecting a suitable conducting pipe with the cored passage 16 of the hopper, it is pointed out that this cored passage may be screw threaded as at 22 to receive the similarly formed end 20 25 23 of a conducting pipe, such as clearly shown in Fig. 1. By this arrangement, it will be noted that the force feed medium from the conducting pipe will be introduced directly into the cored passage 16 and thence 30 conducted to the nozzle member as above stated. The nozzle member opens into the hopper at a point materially spaced from the upper end thereof thereby directing the force feed medium across the hopper such 35 as is obvious. In this form of the invention, I contemplate casting the base 10 integral with the hopper structure, such as above referred to as well as the annular flange 14, whereby the entire dome structure 40 of the device being in one piece, may be manufactured at a greatly reduced cost and at the same time manipulated with greater ease.

In order to lock the base and the hopper 45 structure in connection with the dome 18, I provide a locking nut 24 which, as shown in Fig. 1, is to be positioned on the screw threads 11 of the base and engaged with the outer wall of the dome. In order to expedite cleaning of the interior bore of the nozzle member, especially after the casting of 50 the hopper, I preferably provide the latter with a detachable plug or stopper 25 (see Figs. 1 and 2) whereby access to the interior bore may be readily had. This stopper, however, is not essential and may be eliminated if it is so desired.

A joint structure or goose neck 26 may be 55 detachably connected with the base 10 as shown at 27, whereby it may receive the sand from the dome directly from the hopper structure. The goose neck may be suitably curved as shown in Fig. 2 so that the sand from the hopper structure will be projected 60 against the curved wall 28 thereof and its

velocity not in any way retarded. On the other hand should the same be projected against an abrupt wall such as in the conventional forms of devices of this nature, the velocity thereof would be greatly retarded, notwithstanding the fact that a backing up or rebounding action would ensue, such as would greatly impair the efficiency of the device. The goose neck is provided with a branch as at 29, which branch 70 projects therefrom at a point appreciably above the plane of the mouth of the nozzle member 19 so as to be entirely out of the way of the sand which is being forced through the goose neck. In other words, it 75 will be noted that the sand will be projected against the curved wall 28 of the goose neck at a point appreciably below the branch 29 so that instead of injuring the branch, it will be guided downwardly by such curved surface by the respective conducting pipes. The branch may be in turn closed by any suitable means, such for instance as by the nipple and cap arrangement 30 and 31 respectively, such as shown in Figs. 1 and 2. 80 This will enable the operator to gain access to the interior of the neck as well as the base 10 and the hopper member at all times, without in any way impeding or interrupting the 85 operation of the device. In other words, the cap 31 may be removed without the nipple or the nipple removed from the branch while the device is in full operation.

Although not essential to the efficient operation of my invention, I may provide novel 100 means that may be operated through the branch 29 for the purpose of cleaning the hopper and the nozzle member and keeping the same clean from all foreign material such as would tend to decrease the velocity 105 of the force feed medium. Attention is now directed to Fig. 3 wherein I have shown a device of this nature that may be formed from a single strand of wire, first bent to form a body structure 32 and subsequently 110 bent to form a handle portion 33 at one end and a spirally curved extension 34 at the other end. This device may be left in the branch and hopper at all times, the extensions 34 thereof fitting snugly about the 115 nozzle member 19 as clearly shown in Figs. 1 and 2. Consequently should the aperture 20 of the nozzle member become clogged or stopped up, the operator may remove the cap 31 or the nipple 30 from the branch and 120 manipulate the handle portion 33 of the wire member to position the ends of the extensions 34 in this aperture by way of the counter-bore 21 or when simply cleaning the exterior of the nozzle member, the extension 125 24 may be operated thereabout in an obvious manner. The wire member 32 will not, under ordinary circumstances, impede the action of the force feed medium as it will be spaced to one side of the counter 130

bore 21 at all times. Therefore, by leaving the wire member in position at all times, the nozzle member may be thoroughly cleaned from the exterior of the dome without the necessity of the operator constructing or using other tools to accomplish this purpose.

Furthermore, by connecting the conducting pipes of the force feed medium, which in the present embodiment may be compressed air or steam, exteriorly of the dome, the operator will have free access to the joint at all times and should a leak occur at this point, it may be easily fixed without the necessity of removing the base and hopper structure from the dome. Should the sand become clogged in the hopper 15, such clogged portions may be easily and quickly removed by way of the branch 29 and, in fact, any difficulties which may occur may be dealt with without the removal of the base and hopper structure from the dome and without the necessity of going into the interior of the dome to accomplish such purpose. While it is true that the base, in the embodiment shown in Figs. 1 and 2, must be first arranged in the interior of the dome, provision is made to insert the structure without the necessity of first entering the same into the dome, such as shown in Fig. 7 and which will be hereinafter fully described.

However, while under ordinary conditions, it has been found desirable to introduce the force feed medium into the cored channel 16 of the hopper, such as shown in Fig. 1, it may be found expedient under certain conditions to introduce this medium at an angle. Therefore, in this connection attention is directed to Fig. 4 of the drawings. In this form, the base 10 is provided with a second cored passage 35 that extends at an angle with respect to the cored passage 16 and which is screw threaded a portion of its length as at 36. Consequently by introducing the screw threaded end 37 of the pipe 38 thereinto, the air traveling through the pipe will be directed into the channel 16 as is obvious. This construction will retard the velocity of the air to a slight extent, or in other words prevent a direct flow into the channel 16. Therefore, it is to be understood that I do not limit myself to the specific positioning of the pipe 38, or the pipe shown in Fig. 1, since either form may be used to advantage.

As stated hereinbefore, I also provide means whereby the base 10 and the hopper structure may be inserted into the respective dome opening 12 without necessity of first positioning the base in the dome. In this form, such as clearly shown in Fig. 7, the flange 14 of the base is eliminated, the screw threads 39 being extended to some extent while the dome opening 12 is also screw threaded as shown at 40. The hopper

structure 15 being of less width than the base may be inserted through the dome opening after which the base may be screwed into place in the usual manner. Subsequent to this operation, a locking nut 70 such as shown at 41 may be screwed upon the threads 39 whereby the base will be locked against accidental movement. This form has been found highly desirable under certain conditions.

In the forms above referred to, the air or other force feed medium is, plainly speaking, introduced behind the sand so as to force the latter directly into the goose neck and thence to the conducting pipe (not shown). However, under certain conditions it has been found necessary to introduce the force feed medium at a point where the sand will be drawn by action of a partial vacuum, into the goose neck and fed partially by action of its own specific gravity. This form consists of a base 42, similar to the base 10 in Figs. 1 and 2, being screw threaded about its periphery as at 43 for reception of the lock nuts 44, while it is also provided with the flange 45, corresponding with the flange 14 in the other form. However, the hopper 46 while being cast integral with the base is constructed so as to eliminate the cored passage ways 16 and 17 and the nozzle member 20. On the other hand, the goose neck 47 is connected with the base 42 in the usual manner as at 48 so as to receive the sand from the hopper 46, while the branch 48 is associated therewith to receive a detachable closing plug 49. The branch 48 may be provided with a threaded aperture 50 to receive the similarly formed end 51 of the conducting pipe 52, whereby the air or other force feed medium will be introduced into the goose neck to act in a plane corresponding with the plane of the general extent of the sand conducting pipe (not shown). The sand from the dome proceeds by action of gravity into the hopper structure 46 while when the force feed medium is introduced into the goose neck, a partial vacuum in the base 42 will be formed so as to draw the sand into the sand conducting pipe. In this form the sand is acted upon from two sources, namely, action of its own gravitational feed and, secondly, by action of the partial vacuum above referred to.

Furthermore, in this form, as well as the ones above referred to, all connections are made exteriorly of the dome so that in case of breakage of any of the parts, the necessity of removing the base and the hopper structure is eliminated. Access may be readily had to the goose neck by way of the branch 48 while the hopper 46 may be cleaned in the manner above referred to. From the foregoing, it will be recognized that the device of my invention consists of but two parts, namely, the base and hopper 130

structure; that may be cast in an integral piece and the goose neck thus may be formed integral with the respective branch thereof. The base may be either operated from the 5 interior of the dome or, as shown in Fig. 7, may be inserted subsequent to the insertion of the hopper structure through the dome opening. The connection which I have shown will retain the base in a secure position 10 with respect to the dome and prevent accidental dislodgment thereof due to the jarring of the locomotive. On the other hand, it will be readily recognized that the sand may be expeditiously fed or forced into 15 the respective conducting pipes and thus uniformly applied to the rail. In the form shown in Figs. 1 and 2, the sand acting upon the curved surface 28 of the goose neck is projected directly into the projecting tube 20 while in the other form the air is directed or introduced into the goose neck in a plane corresponding with the plane of the general extent of the conducting pipe. Believing that the advantages and novel features of 25 the invention will be readily understood from the foregoing, further detail description is deemed unnecessary.

In reducing my invention to practice, I find that the form referred to herein as the 30 most practical and preferred embodiment is the most efficient, but realizing that certain conditions will necessarily vary in concurrence with the adoption of my device, I desire to emphasize the fact that various 35 minor changes in the details of construction and in the proportion of parts may be resorted to when required without sacrificing any of the advantages of my invention as defined in the appended claims.

40 Having thus fully described my invention, what I claim as new and desire to secure by Letters Patent is:—

1. In a sand feeding device of the character described, the combination with a container having a receiving opening, of a tubular base to be received into said opening, a hopper structure to be cast integral with said base and arranged interiorly of the container, means to lock said base in place, a joint structure connected with said base exteriorly of said container, means to create a flow of sand through said base and said joint structure, and a branch on said joint structure whereby access may be had to the interior of said base and said hopper, as and for the purpose specified.

60 2. In a sand feeding device of the character described, the combination with a sand container having a receiving opening, of a tubular base to be received in said opening, a hopper associated with said base to be arranged interiorly of the container, a goose neck connected with said base exteriorly of the container, a branch on said 65 goose neck, means to normally close said

branch, and means to introduce a force feed medium through said goose neck to create a flow of sand from said hopper, as and for the purpose specified.

3. In a sand feeding apparatus, a base 70 structure to be associated with the sand dome, a hopper carried by said base structure to be arranged interiorly of the dome, a joint structure connected with said base structure exteriorly of said dome, means to 75 create a flow of sand from said hopper structure through said base and said joint structure, a branch on said joint structure whereby access may be had to the interior of said base and said hopper from a point 80 exteriorly of the container, and said branch being arranged to be out of the path of flow of sand, as and for the purpose specified.

4. In a sand feeding device, the combination 85 with a sand dome having a receiving opening, of a tubular base to be inserted into said opening, a hopper structure substantially semi-circular when viewed in cross section cast integral with said base, 90 means to lock said base in position, a joint structure connected with said base exteriorly of said container, means to introduce air under pressure into the device to cause a flow of sand from said hopper through 95 said base and said joint structure, a branch on said joint structure whereby access may be had to the interior of said base and said hopper, means to close said branch and said branch being disposed at an angle to be out 100 of the path of flow of the sand, as and for purpose specified.

5. In a sand feeding device of the character described, the combination with a sand container having a receiving opening, 105 of a base to be inserted into said receiving opening, a hopper cast integral with said base to project into the interior of said container and receive the sand by gravitational feed, a goose neck connected with 110 said base exteriorly of said container, a branch on said goose neck substantially intermediate its ends, means to normally close said branch, means to create a flow of sand from said hopper through said goose 115 neck, and said branch being arranged to be above the flow of sand whereby access may be had to the interior of said base and said hopper during the flowing of the sand, as and for the purpose specified.

6. In a sand feeding device, the combination 120 with a dome, of a tubular base to be associated with the dome, a hopper structure cast integral with the base to project interiorly of the dome and receive the sand, 125 a nozzle member formed integral with said hopper structure, said base and said hopper structure being provided with a cored passage way to communicate at one end exteriorly of said dome and at the other end 130

with said nozzle member, whereby a force feed medium may be introduced to said nozzle member from a point exteriorly of the dome to eject the sand from said hopper structure through the base, and a joint structure connected with said base and adapted to convey sand to its destination and allow inspection of the sand thus being conveyed.

7. In a sand feeding device of the character described, a tubular base, a hopper structure cast integral with the base to communicate with the interior bore thereof, said base and said hopper structure being provided with a cored passage way whereby a force feed medium may be introduced into said hopper structure to force the sand through said tubular base, a goose neck connected with said base, and a branch on said goose neck whereby access may be had to said base and said hopper structure, as and for the purpose specified.

8. In a sand feeding device of the character described, the combination with a sand dome, of a tubular base to be associated therewith, a hopper structure cast integral with said base to project interiorly of the dome, said base and said hopper structure having a cored passage way opening at one end exteriorly of the dome and at the outer end at a point adjacent the inner end of the hopper and spaced from the inner wall of the dome, whereby a force feed medium may be introduced to the hopper at a point exteriorly of the dome to cause the flowing of the sand through said tubular base, a goose neck connected with said base exteriorly of said dome, a branch on said goose neck whereby access may be had to said base and said hopper structure during the flowing of the sand, and means to lock said base structure in position, as and for the purpose specified.

9. In a sand feeding device of the character described, the combination with a dome having a receiving opening, of a tubular

base to be positioned in said opening, a hopper structure cast integral with said base to be positioned interiorly of the dome, said base and said hopper structure provided with a cored passage way opening at one end exteriorly of said dome, a nozzle member cast integral with said hopper at a point adjacent its inner end and spaced from the inner wall of the dome, the other end of said cored passage way communicating with said nozzle member, whereby a force feed medium may be introduced to said hopper structure from a point exteriorly of said dome, whereby the flowing of the sand through said tubular base may be obtained, a goose neck connected with said base exteriorly of said dome, a branch on said goose neck to be above the flow of sand whereby access may be had to the interior bore of said base and said nozzle member from a point exteriorly of the dome, and means to lock said base structure in position, as and for the purpose specified.

10. In a sand feeding device of the character described, the combination with a sand dome of a tubular base to be associated with said dome, a hopper structure cast integral with the base to be positioned interiorly of the dome, a joint structure connected with said base exteriorly of the dome, a branch on said joint structure whereby access may be had to the interior bore of said base and said hopper, and means to direct a force feed medium through said joint structure whereby sand from said hopper structure will be drawn through said base and through said joint structure, as and for the purpose specified.

In testimony whereof I affix my signature in presence of two witnesses.
